[57] CLAIM

The ornamental design for a toy cupboard, as shown and described.

DESCRIPTION

FIG. 1 is a top, front and side perspective view of a toy cupboard showing my new design;

FIG. 2 is a side elevational view thereof from the left of FIG. 4, the side opposite that shown in FIG. 2 being the mirror image thereof;

FIG. 3 is a top plan view thereof;

FIG. 4 is a front elevational view thereof; and,

FIG. 5 is a rear elevational view thereof.

FIG. 1

FIG. 2

FIG. 3

FIG. 4

FIG. 5
